CLEANING ROLL

Peter J. Massey, River Forest, Ill., and William F. Thiele and Bert F. Raprager, Wisconsin Rapids, Wis., assignors, by mesne assignments, of nine-tenths to Consolidated Water Power & Paper Company, Wisconsin Rapids, Wis., a corporation of Wisconsin, and one-tenth to said Peter J. Massey

Application November 27, 1935, Serial No. 51,739

7 Claims. (Cl. 91—48)

This invention relates to improvements in means for cleaning rolls or drums, and refers specifically to the use of a stone, granite or artificial stone roll which is adapted by making rolling

5 contact with another roll or drum to remove foreign substances, such as fibre, lint, coating material, etc., from the surface of said latter roll or drum.

In our co-pending application for United States 10 Letters Patent Serial No. 40,150, a machine is described for coating paper which is adapted to carry out the processes of Peter J. Massey described in United States Patents Nos. 1,921,368 and 1,921,369. In the Massey coating process 15 coating material is applied by rolls to the surface or surfaces of a continuously passing web of paper, the coating material carried by the rolls being in the form of a continuous, smooth, uniform film which, in effect, is transferred bodily 20 to one or both surfaces of the web. In view of the fact that the coating when applied to the web is in finished condition, in so far as its smoothness and distribution is concerned, it is essential 25 that the coating film on the roll surface be smooth and undisturbed or unmarred by any foreign substance. If foreign substances are carried by the roll prior to the time when the coating material is applied thereto, said substances in all probability will be embedded in the coating applied 30 to the web. Therefore it is imperative that the coating roll be maintained in an extremely clean condition.

Our present invention is particularly directed 35 to the cleaning of a roll such as above described, and the efficacy thereof is dependent upon the phenomenon which is inherent in a stone, granite or artificial surface and which is characterized in that foreign particles, such as lint, fibres, coating material and the like adhere to such surfaces 40 even if dry, when the same are brought in osculating relation with a roll surface which is to be cleaned.

Of course, it is to be understood that, our invention although particularly adaptable for cleaning 45 coating roll surfaces such as above described, can be used to clean surfaces of rolls or the like used for other purposes wherein clean surfaces are necessary.

Other objects and advantages of our invention 50 will be apparent from the accompanying drawing and following detail description.

The single drawing illustrates a diagrammatic side elevational view of our roll cleaning device.

Referring in detail to the drawing, 1 indicates 55 a roll or drum which is mounted upon bearings

2 positioned at opposite ends of the roll. The bearings are mounted upon opposite standards or supports 3 which may be of conventional construction.

Roll 1 may be a coating roll or the like and may be adapted to carry a mobile substance upon its surface which is adapted to be transferred to the whole or a portion of the surface of a continuously advancing flexible web 4. Roll 1 may be adapted 10 to cooperate with a similar roll 5 which may also carry a mobile substance upon its surface which is to be transferred to the opposite or upper surface of the web 4. The web 4 passes between rolls 1 and 5 at their point of contact. The coating material or other mobile substance may be transferred to roll 1 by means of osculating form rolls 6 which in turn may be contacted by distributing rolls (not shown) which transfer the mobile substance from a suitable source of supply (not shown) to the surfaces of the form rolls 20 6. If both faces of the web 4 are to be treated or coated a similar arrangement may be utilized with roll 5.

The peripheries of rolls 1 and 5 move in the same direction, and in most cases, at the same 25 peripheral speed as web 4. In utilizing our invention it is necessary to apply the mobile substance between the point of cleaning and the point of transfer of the coating to the web surface, that is, the rolls 6 preferably contact roll 1 30 on its advancing side taken with reference to the point of contact with the web.

In the operation of the machine, which comprises the subject matter of our co-pending application hereinbefore mentioned, the films of 35 coating material transferred from rolls 6 to the surface of roll 1 are uniformly distributed, smooth and of compact texture. These films are transferred bodily to the web surface, it being intended that the film upon the web be as smooth and 40 uniformly distributed as that on the roll. Consequently it is essential that that portion of the surface of roll 1 to which the films are applied be as clean and smooth as possible, since any irregularity such as the presence of fibres, lint 45 or coating material upon the roll 1 over which the films are applied will appear as an irregularity upon the coating applied to the web.

Many operations other than the specific example given above require clean, smooth applicator rolls. Therefore we do not wish to be limited to that one specific application of our present invention since it broadly contemplates the cleaning of the surface of any roll used for analogous 55 purposes.

Referring again to the drawing, 7 indicates one of a pair of oppositely disposed standards, which are pivotally supported, as at 8, to oppositely positioned lugs or bases 9. The upper ends 5 of the standards 7 carry bearings 10 which, in turn, support the opposite ends of roll 11. As will be hereinafter described, roll 11 is adapted to be disposed in osculating relationship with the receding surface of roll 1, taken with reference to 10 the point of tangency of web 4.

Each of the standards 7 is provided with outwardly extending arms 12 which are pivotally secured to piston rods 13. Cylinders 14 are pivotally supported, as at 15, to lugs or bases 16. The 15 piston rod 13 at each side of the device passes through stuffing boxes 17 in the heads of the respective cylinders 14 and a piston 18 is secured to the end of each of said rods.

In operation, air or other fluid under pressure 20 may be introduced into the cylinders 14 beneath the pistons 18 thereby urging the rods 13 upwardly and tending to rock standards 7 in a counterclockwise direction. Roll 11 is thereby urged toward roll 1 and is maintained in contact therewith, preferably under pneumatic pressure.

It is to be understood, that the piston rod and cylinder, if desired, may be respectively connected to standard 3 and standard 7, whereby inward motion of the piston within the cylinder will 30 bring the rolls 1 and 11 together. This arrangement of the actuating piston and cylinder mechanism is not shown, but is an obvious mechanical expedient which will be easily understood by, and may be helpful to those skilled in the art.

35 A bushing 19 is pivotally secured to each standard 3, as at 20, each of said standards carrying a lug 21 to which said bushing is attached. A bushing 22, having a slot 23 at its end is adapted to be pivotally secured to each standard 7, each standard carrying a pin 24 which passes through each aperture 23. A capstan screw 25 is adapted to threadedly engage each pair of bushings 19 and 22, the threads at opposite ends of the screws being differentially pitched in the same direction or oppositely pitched so that motion of the capstan relatively moves the standards 3 and 7 closer together or further apart. Standard 7 is provided with an oversize aperture 26 so that bushing 22 may move angularly in a vertical plane.

50 The arrangement is such that adjustment of capstan screw 25 limits the degree of proximity of standards 3 to 7 and hence rolls 1 to 11. If it is desired to separate rolls 1 and 11, fluid under pressure may be introduced into cylinder 14 above piston 18 and the pressure beneath said piston may be relieved in which case standard 7 is rocked clockwise a distance limited to the effective 55 length of slot 23. The effective length of slot 23 may be changed by set-screw 27 which may protrude into the end of slot 23. In this manner roll 11 may be conveniently rocked away from roll 1 for purposes of cleaning or repair.

As a feature of our invention, roll 11, or at least the surface thereof, is constructed of 65 granite, or other form of stone, or artificial stone such as "Stonite" or the like. We are aware that cleaning rolls have heretofore been used which by means of rolling contact with a second roll have acted to clean said latter roll. However, 70 in substantially all cases said cleaning rolls carry a film of water or other liquid upon their surface. Our cleaning roll may, if desired, be operated in the dry state. Further, we are aware that granite, stone or artificial stone rolls have here- 75 tofore been used, particularly in the paper making

industry. However, their use has been confined to operations other than the cleaning of another roll. We have found that, a stone or artificial stone roll has the peculiar faculty for "picking up" loose materials such as fibres, lint, etc. This phenomena appears to be a characteristic of such a surface which, to our knowledge, has not been heretofore recognized and the affinity for such materials by a granite, stone or artificial stone roll exhibits itself even when the cleaning roll is 10 maintained in the substantially dry state.

The foreign materials picked up by roll 11 from the surface of roll 1 may be removed from the surface of the first mentioned roll by a scraper blade 28 which may be adjustably mounted, as by 15 means of bolt 29, upon arm 30. Arm 30, in turn, may be adjustably secured to lug 31 which comprises a continuation of standard 7. Another advantage inherent in the use of a stone roll is that, a metal scraper blade will not in any way 20 detrimentally affect the surface of the roll, said surface remaining continuously perfect in spite of the continuous rubbing or scraping contact of the blade 28.

By the use of the expression "stone roll" as 25 used in the specification and claims, is meant: A roll constructed wholly or in part (surfaced) of stone, granite, rock, artificial stone or rock or the like.

We claim as our invention:

1. In combination, a roll for applying coating material to a continuously passing flexible web, and a stone roll disposed in osculating relationship with said first mentioned roll to clean the surface of the same. 30

2. In combination, a roll for applying coating material to a continuously passing flexible web, and a substantially dry stone roll disposed in osculating relationship with said first mentioned roll to clean the surface of the same. 35

3. In combination, a roll for applying coating material to a continuously passing flexible web, a stone roll disposed in osculating relationship with said first mentioned roll to clean the surface of the same, and means for resiliently holding the 40 surfaces of said osculating rolls in contact with each other. 45

4. In combination, a rotating coating roll, a stone roll osculating therewith and travelling at substantially the same peripheral speed as said first mentioned roll for cleaning the surface of 50 said first mentioned roll.

5. In combination, a rotating coating roll, a stone surfaced roll osculating therewith and travelling at substantially the same peripheral speed as said first mentioned roll for cleaning the surface of 55 said first mentioned roll.

6. In combination, a rotating coating roll, a substantially dry roll having a stone surface osculating with said first mentioned roll and travelling at substantially the same peripheral speed 60 therewith for cleaning the surface of said first mentioned roll.

7. In combination, a rotating coating roll, a roll having a stone surface osculating with said 65 first mentioned roll and travelling at substantially the same peripheral speed as said first mentioned roll for cleaning the surface of said first mentioned roll, and means for removing foreign matters carried by said stone surface roll transferred 70 thereon from said first mentioned roll.
